(57) **CLAIM**

The ornamental design for a dental bone guide as shown and described.

DESCRIPTION

FIG. 1 is a first perspective view of a dental bone guide, showing our new design;

FIG. 2 is a second perspective view thereof;

FIG. 3 is a third perspective view thereof;

FIG. 4 is a right elevation view thereof;

FIG. 5 is a left elevation view thereof;

FIG. 6 is a rear elevation view thereof; and,

FIG. 7 is a front elevation view thereof.

All broken lines are included for the purpose of illustrating use and environment and form no part of the claimed design.

1 Claim, 3 Drawing Sheets
